UNITED STATES PATENT OFFICE.

LARS EDWARD LARSON AND DANA R. CORNELL, OF EAST CHICAGO, INDIANA, ASSIGNEES TO STANDARD FORGINGS COMPANY, OF CHICAGO, ILLINOIS, A CORPORATION OF ILLINOIS.

ROTATABLE SPINDLE FOR TAILSTOCKS.

Application filed August 24, 1925. Serial No. 51,910.

This invention relates to improvements in tail stocks for lathes with rotatable spindles.

In heavy duty lathes and similar machine tools used for removing large amounts of metal with a cutting tool or removing same simultaneously with a plurality of cutting tools, difficulty has been experienced not only in preserving the life of the tail stock spindle and its center and keeping the latter in proper condition, but also in keeping the work being operated upon in proper condition,—the heavy load, the radial pressures and thrusts, and other causes producing sticking, heating, distorting and mutilation not only of the article being machined but also of the tail stock center, and causing undue wear and shortening the life of the tail stock center.

The principal object of the present invention is to produce a construction of rotatable spindle by the use of which sticking and overheating and the other difficulties will be entirely avoided; a construction which will sustain heavy thrusts and excessive radial pressures without injury or mutilation to the work or to the tool; a construction which will not only be compact but will sustain increased radial and load capacity over known constructions of similar size; a construction which will be adaptable to the tail stock of machines now on the market without altering the general outside dimensions of standard tail stock castings; a construction which will provide for adjustment of the bearings as wear takes place and take up any looseness of the spindle when it occurs, whereby the central or axial line of the spindle will be maintained in its original position; a construction which will permit of proper lubrication and yet reduce the frequency of relubrication to a minimum; and generally, to produce a construction which will be compact, durable, which will serve the purposes intended, and which will remain in order for an indefinite period and prolong the life of the machine.

These and other objects and advantages of the invention will become apparent as we proceed with this specification, the invention consisting of the devices and combination of devices herein illustrated and described and more particularly set forth in the appended claim.

In that form of our invention which we have chosen for purposes of illustration in the accompanying drawings:

Figure 1 is a side elevation of a lathe tail stock embodying our invention.

Figure 2 is an end elevation of the same, and

Figure 3 is a sectional plan view, enlarged, the section being taken upon the horizontal plane indicated by the dotted line 3—3 on Fig. 1.

In said drawings, A indicates a tail stock housing of any conventional form or type, provided with a base 1, whereby it may be movably secured in operative position upon a lathe, and having a cylindrical, longitudinally apertured body portion 2 adapted to receive a movable, cylindrical spindle holder B. Within the holder B is a spindle C which carries the tool-center D.

The body 2 is longitudinally bored as indicated at 3 to afford a bearing support for the holder B, the rear end of the body bore being closed by plug cap E, having screw threaded engagement with the body 2 as indicated at 4. The tail stock A and cap E will usually be made of cast iron, while the holder B, spindle C and center D will usually be made of steel.

The holder B is provided at one end with an enlargement, and at its other end the holder is provided with a steel nut 7 and, preferably, also with a bronze bushing 8 between the nut 7 and the interior wall of the holder. A steel screw 9 of considerable relative length passes through this nut 7. It carries a non-threaded shank 10 which passes through the cap E and through a hand operating member or wheel F, which latter is firmly secured by the nut 11. The hub 12 of the wheel member bears as shown upon the outer face of the cap E while a shouldered ring 13 on the shank 10 bears against the inner face of the cap. The nut 7 and the bushing 8 may be suitably locked by the screw bolt 14. It will be understood by this arrangement that the holder B may be moved longitudinally of, and thus suitably adjusted within, the body 2 of the tail stock by means of the screw 9 actuated by the operating member F.

The holder B is of tubular form as clearly shown, the interior spaces being of three different diameters, as indicated by 15, 16 and

17. In the space 15 is a combined radial and thrust bearing, indicated as a whole by the letter G and in the space 17, is a similar bearing indicated as a whole by the letter 5 G'. These bearings G, G' are well known to the art and as they form no part, per se, of this invention, and only as a "bearing" in connection with the other features, need not be herein more fully described. The inner 10 rings 18 and 19 of said bearings, however, are of an interior diameter to receive and support the respective end portions of the rotatable spindle C, the latter however having no bearing or contact with the wall of 15 the central portion 16, as shown.

It will be noticed that the inner ring member 18 is held against rear-shifting movement relative to the spindle by the adjusting nut 20, lock nut 21, washer 22 and will 20 therefore rotate with the spindle. Also that the inner ring member 19 is held against longitudinal outward movement relative to the spindle by the washer plate 26 on the spindle and interposed between the end of 25 the ring member 19 and the inner face of the annular enlargement 23 of the spindle. Said ring 19 will therefore also rotate with the spindle. It will be understood that by this construction any looseness in the bearing 30 G, G' due to wear or other cause, may be readily taken up and corrected by the adjusting nuts 20, 21.

Dust and dirt may be kept out of the space 35 17 by means of the cup shaped ring guard 24 positioned therein and having an inwardly directed annular flange member 25 overlapping a washer plate 26.

The spindle C is interiorly bored at 27 to receive the free end of the screw 9 and 40 at 28 to form a bearing for the steel center D, the aperture 28 being outwardly tapered as shown to conform to the conical or tapered circumferential area of the center D, the working point 29 of which suitably projects beyond the face of the enlarged 45 portion 23 of the spindle C.

The spindle holder B is locked against movement of rotation within the body 2 of the tail stock by a set screw key 30, or in 50 any other suitable manner. The screw bolt 32 closes an oil hole radially extending 35 through the wall of the holder B whereby a suitable lubricant may be inserted to fill the spaces 15, 16 and 17. The space 3 may 55 also be provided with a suitable lubricant.

From the construction described, it will be understood that when the article to be operated upon, say a car axle, for example, in a lathe provided with this invention, is 60 suitably positioned, the point 29 of the center D will be engaged with the "center" in the end of the axle and suitably tightened thereto by the sliding forward of the holder B under the influence of the adjusting member F. The rotation of the axle as the op-

eration proceeds, will cause the rotation of the center D and spindle C and this will be facilitated by the antifriction bearings G, G'. Heating of the center and of the drilled center in the axle will be entirely 75 eliminated, and all mutilation or distortion of the axle obviated. Also the life of the center D will be indefinitely prolonged since rotating with the axle, it does not become scored or broken by reason of heavy bearing loads, sticking, excessive radial pressures or other causes.

One of the advantages obtained by our invention is the elimination of need for lubrication of the center D. Where such 80 centers are fixed, the need of and consequent expense of lubrication is caused by heating due to rotation of the work about a non-rotatable center, at its point, such as point 29, this being entirely avoided where the 85 center D rotates with the work.

It will also be noted that the device is compact and relatively small, is adapted to be the tail stock of many if not all of the conventional lathes on the market, may be 90 quickly adjusted, easily lubricated and by reason of its design, will in fact require lubrication only once a year under normal conditions of use.

While we have described the preferred 95 form of our invention which, after a successful and satisfactory use for a considerable period of time, we recommend as a desirable form for most purposes, yet other 100 forms may be used and changes and modifications as to details may be made without departing from the principle of our invention, and therefore we do not desire to be limited herein to the particular details herein illustrated and described, except as pointed out in the claim hereto appended.

We claim as our invention:

A tail stock unit adapted to retain a body of lubricant for its movable parts, comprising a fixed support having a cylindrical, radially contractable body portion closed at one end, a cylindrical spindle holder closed at one end slidably mounted within said body portion, means journaled in the closed end of said body portion and operatively engaging the closed end of said spindle holder for axially adjusting said spindle holder in said body portion, spaced bearings mounted within said spindle holder, a rotary spindle supported on said bearings and extending through the open end of said spindle holder, a washer plate closing the space between said rotary spindle and said spindle holder adjacent its open end, and a work center carried by said rotary spindle.

In testimony that we claim the foregoing as our invention we affix our signatures this 20th day of August, 1925.

LARS EDWARD LARSON.
DANA R. CORNELL.
